John B. Pierce Inventor.
By James Saenger, Attorney.

UNITED STATES PATENT OFFICE.

JOHN B. PIERCE, OF BUFFALO, NEW YORK.

DESIGN FOR A RADIATOR.

SPECIFICATION forming part of Design No. 21,028, dated September 1, 1891.

Application filed February 9, 1891. Serial No. 380,828. Term of patent 7 years.

To all whom it may concern:

Be it known that I, JOHN B. PIERCE, a citizen of the United States, residing in Buffalo, in the county of Erie and State of New York, have invented and produced a new and original Design for Radiators, of which the following is a specification, reference being had to the accompanying drawing, forming a part thereof, in which is represented a perspective view of one of my newly-designed radiators.

At the upper portion of the sections, at both sides of the same, facing outward, is the representation of a lion's head 2, and below that the body of the section 1 is plain; but the essen-

tial feature is the lion's head at the front and 15 rear portions of the upper part of the radiator. The lower portions of the sections may be either plain or have an ornamental portion. The feet 5 of the end sections are made in imitation of a lion's leg and paw. 20

I claim as my invention—

The design for a radiator, substantially as herein shown and described.

JOHN B. PIERCE.
